UNITED STATES PATENT OFFICE

FRANK A. BROWNE, OF WAYNE, PENNSYLVANIA, ASSIGNOR TO THE BARBER ASPHALT COMPANY, OF PHILADELPHIA, PENNSYLVANIA, A CORPORATION OF WEST VIRGINIA

SEPARATOR

Application filed February 13, 1928. Serial No. 253,962.

This invention relates to a device for separating a liquid from a vapor and more particularly to a device for separating a liquid from a vapor soluble therein especially when the liquid is carried by the vapor as a fine mist or spray.

A refrigerating apparatus of the type in which the vapors of a volatile refrigerant are compressed by a lubricated compressor 10 presents the type of problem in its operation which this separating device is designed to solve. If, for example, the refrigerant is ethyl chloride and mineral oil is used as a lubricant for the compressor, the ethyl 15 chloride vapors which the compressor delivers carry the oil as a fine mist which is not readily separated from the vapors. If this oil is permitted to enter the boiler with the refrigerant it may be permanently lost 20 to the compressor and eventually all of the lubricant used will be in the boiler, necessitating both frequent renewal of lubricant and draining of the boiler.

Furthermore, since ethyl chloride is soluble 25 in mineral oil, the lubricating oil is so diluted that it fails to function properly as a lubricant and seal in the compressor.

The objects of this invention are accordingly the provisions of means for separating 30 a mist of the type described from a vapor or gas and for removing dissolved vapors from a liquid.

In the drawing:

Fig. 1 is a vertical section through the 35 separator; and

Fig. 2 is a plan view thereof.

The separator comprises a chamber 2, shown as a rectangular box of sheet metal, into which extends an inlet tube 4 continued 40 within the chamber as a spiral 6 at one end of the chamber and a second spiral 8 at the other end and opening at 10 near the top of the chamber.

A tube 12 opening adjacent the top of chamber 2 provides an exit for vapors entering the chamber. Extending in a vertical plane across the chamber on opposite sides of tube 12 are perforated baffle plates 14. These plates are joined midway of their heights by 50 an imperforate baffle plate 16 which extends

from front to rear of the chamber. A second horizontal baffle plate 18 which is perforated, is located between baffle plates 14 and the front and rear walls of the casing above plate 16 and below the open end of tube 12 55 which passes through a circular opening therein.

The chamber may be supplied with liquid through a filling plug 20.

Communicating with the bottom of the 60 chamber is a heating device comprising an outer shell 22 within which is secured, by screw threads, for example, an inner shell 24 which forms a casing for an electrical heating coil 26, the lead in wires to which are 65 located within a conduit 28. The walls of shells 22 and 24 form an annular liquid receiving chamber with the bottom of which an exit tube 30 communicates.

As an example of a system in which this 70 separator may be used, reference may be made to application Serial Number 253,961, filed February 13, 1928, which shows a refrigerating system with the separator included 75 therein. In using ethyl chloride as a refrigerant and mineral oil as a lubricant in such refrigerating system, a compressor would be arranged to discharge refrigerant under compression into tube 4, which refrigerant would carry lubricant from the compressor in the 80 form of a fine mist. This mist carrying vapor would be forced through spirals 6 and 8 and discharged into the chamber at 10. It is found that if tube 4 be about five feet in length that the droplets forming the mist 85 coalesce to form larger globules which readily separate centrifugally in the spirals from the ethyl chloride vapors and collect in the chamber 2, so that the vapors collecting above the lubricant in the chamber and passing into 90 outlet tube 12 are substantially free from oil. In the refrigerating system disclosed in the copending application referred to above, outlet tube 12 communicates with a condenser and boiler from which it is necessary to exclude 95 lubricating oil as far as possible.

The lubricant entering from the compressor or pump collects in the bottom of the chamber and the level is maintained either at that of baffle plate 16 or below the same. If a vola- 100

- tile substance such as ethyl chloride is dissolved in a more or less viscous liquid such as lubricating oil and the pressure thereon is suddenly released, foaming is apt to occur.
- 5 The object of the baffle plates surrounding tube 12 is to prevent foam from rising above the open end of this tube thereby permitting oil to pass out therethrough. If foaming occurs in the construction shown, that formed 10 in the vicinity of tube 12 will pass beyond the ends of plate 16 and will be effectively broken up in its rise through perforated plates 14 and 18, so that none of it will reach the open end of tube 12 under any normal conditions of operation.
- 15 The lubricant passes out through the heater and tube 30 to the compressor. As stated above, lubricating oil dissolves ethyl chloride and by so doing is rendered too dilute to function as a lubricant and because of the ease with 20 which the ethyl chloride is evaporated therefrom it fails to act as a liquid seal in a rotary compressor. The heater warms the oil sufficiently to boil off ethyl chloride from solution 25 and also serves to heat the oil to maintain desired fluidity. The baffle plates also serve to prevent the passage of lubricant into outlet 12 during the foaming resulting from this boiling.
- 30 Having now fully described my invention, what I claim and desire to protect by Letters Patent is:
1. A separator comprising a chamber, an inlet conduit opening into the chamber, an 35 outlet tube extending upwardly within said chamber with an open end above a normal liquid level within said chamber, a plate extending horizontally about said tube below its open end and adjacent said normal liquid 40 level, and perforated baffle plates arranged to break foam rising about the edges of the first named plate.
2. A separator comprising a chamber, a spiral tube of substantial length and relatively small internal diameter adapted to separate liquid centrifugally from vapors and 45 opening above a normal liquid level within said chamber, an outlet tube extending upwardly within said chamber with an open 50 end above said normal liquid level within said chamber, a series of baffle plates arranged to prevent foam from the liquid from entering the open end of said tube, and a heated outlet for liquid in said chamber.
- 55 3. A separator comprising a chamber, a spiral tube of substantial length and relatively small internal diameter opening above a normal liquid level within said chamber, an outlet tube extending upwardly within 60 said chamber with an open end above said normal liquid level within said chamber, a series of baffle plates arranged to prevent foam from the liquid from entering the open end of said tube, a shell having an open end 65 communicating with the aforementioned
- chamber and a second shell enclosing a heating element and located within said first mentioned shell, whereby the walls of the shells form an annular liquid receiving space about the heating element, said liquid receiving space having an outlet whereby liquid may flow from the chamber through said liquid receiving space.
4. A separator comprising a chamber, an inlet conduit opening into the chamber, an 70 outlet conduit opening above a normal liquid level within said chamber, a plate extending horizontally below the opening of the outlet conduit adjacent said normal liquid level, and perforated baffle plates arranged about the opening of the outlet conduit and adapted to break foam rising about the edges of the first named plate before it reaches the opening of the outlet conduit.
- 75 In testimony of which invention, I have 80 hereunto set my hand, at Philadelphia, on this fourth day of February, 1928.
